DES. 2281

F. A. Giles of New York, N.Y.

Letter Patent No. 2281 Dated Mar. 13th 1866.

Design for a Top plate for a Watch

The schedule referred to in this Letter Patent & making part of the same

To all whom it may concern:

Be it known that I, Frederick A. Giles, of the City, County and State of New York, have invented a new Design for the Top Plate of a Watch; and I do hereby declare that the following is a full clear and exact description of the same referring being had to the annexed drawing, making part of this specification, and drawing representing a plan view of a watch, with the cap, balance cock and balance removed to show the design of the plate, A, which is tinted yellow to distinguish it from the other parts.

This plate, A, is flat and of the form of a circle except that in one side of it there is a circular recess, B, which conforms to the exterior circumference of the spring barrel, B, and the interior line of which unites with the line of the outer circumference of the plate, A, by two salient curves, C, C. Near the margin of the plate and on the opposite side of the center thereof to that on which the circular recess, A, A, is situated, there is an opening, E, F, G, H, in the longitudinal centre of which is a line passing through the centre of the pivot hole, I, of the staff of the lever, and through the centre of the pivot hole, J, of the escape-wheel spindle, which holes are situated respectively in the central portions of the inwardly projecting parts of the plate at the ends, E, F, and G, H, of the said opening. The sides, E, G, and I, H, of the said opening have salient curvatures, and these meeting in points with the re-entering curvatures in the ends, E, F, and G, H, give the opening a form having some resemblance to that of

two crevets placed back to back.

What I claim as my invention and desire to secure by
Letters Patent is,

The design and configuration of the plate of
a watch substantially as herein described and represented

in the accompanying drawings.

J. A. Gile.
